CLAIM

The ornamental design for a drawer for refrigerator, as shown and described.

DESCRIPTION

1. Drawer for Refrigerator

1.1 is a perspective view of a drawer for refrigerator, showing our new design;

1.2 is a front elevation view thereof;

1.3 is a rear elevation view thereof;

1.4 is a left-side elevation view thereof;

1.5 is a right-side elevation view thereof;

1.6 is a top plan view thereof;

1.7 is a bottom plan view thereof;

1.8 is a perspective view thereof, in a use condition;

1.9 is a perspective view of the drawer for refrigerator, when the drawer is slid out;

1.10 is a front elevation view thereof;

1.11 is a rear elevation view thereof;

1.12 is a left-side elevation view thereof;

1.13 is a right-side elevation view thereof;

1.14 is a top plan view thereof;

1.15 is a bottom plan view thereof;

1.16 is a perspective view thereof, in a use condition;

1.17 is a perspective view of the drawer for refrigerator, when the drawer is slid out and each of the baskets therein slides to each side;

1.18 is a front elevation view thereof;

1.19 is a rear elevation view thereof;

1.20 is a left-side elevation view thereof;

1.21 is a right-side elevation view thereof;

1.22 is a top plan view thereof;

1.23 is a bottom plan view thereof; and

1.24 is a perspective view thereof, in a use condition.

The broken lines shown in the drawing figures are included for the purpose of illustrating environment and form no part of the claimed design.
